UNITED STATES PATENT OFFICE.

WALTER S. LAUFFER, OF NEW MATAMORAS, OHIO.

ANTISKIDDING ATTACHMENT FOR AUTOMOBILE-TIRES.

1,115,692.

Specification of Letters Patent. Patented Nov. 3, 1914.

Application filed March 24, 1914. Serial No. 826,956.

To all whom it may concern:

Be it known that I, WALTER S. LAUFFER, a citizen of the United States, residing at New Matamoras, in the county of Washington and State of Ohio, have invented certain new and useful Improvements in Antiskidding Attachments for Automobile-Tires, of which the following is a specification, reference being had to the accompanying drawings.

This invention relates to anti-skidding attachments for automobile tires.

One object of the invention is to provide an article of this character that shall be simple of construction, of the highest efficiency and durability in use, and capable of ready attachment to position upon a tire, the arrangement of the parts being such as to enable them to resist strain without any appreciable deterioration, and in which, in case of damage, repairs may easily and readily be effected.

A further object is to provide an anti-skidding attachment which may be used in connection with a common twisted link chain, so that to apply the present invention to an automobile tire will require only the exercise of ordinary mechanical skill.

With the above and other objects in view, as will appear as the nature of the invention is better understood, the same consists in the novel construction and arrangement of parts of an anti-skidding attachment for automobile tires, as will be hereinafter fully described and claimed.

In the accompanying drawing forming part of this specification, and in which like characters of reference indicate corresponding parts: Figure 1 is a view in side elevation displaying the manner in which the attachment is combined with an ordinary twisted link chain; Fig. 2 is a view in side elevation of the anti-skidding attachment, partly in section.

The attachment is constructed from any suitable material, preferably from malleable cast iron, and embodies a semi-band 1 the arch of which will closely approximate the contour of the tire, so as to avoid cutting due to the rubbing action between the attachment and the part to which it is joined. Each terminal of the semi-band is provided with two out-standing lugs 2 that are transversely orificed, for a purpose that will presently appear.

Carried by the bend of the band are two spurs 3, each having a threaded shank 4 and an intermediate nut 5, the spurs being preferably of hard steel in order to cause them to be capable of resisting long continued wear without appreciable deterioration. The nuts are seated in sockets 6 arranged on the outer face of the band, the sockets being of a depth to house the greater part of the length of the nut, so that the spurs will be free to engage with the surfaces over which the machine is traveling, and the nuts will be protected from wear.

In assembling the bands with the chains 7, one being employed on each side of the tire, two adjacent links are slipped over the pair of lugs at each end of the band, and a wire 8 is then threaded through the crifices 9 of the lugs and the ends of the wire are wrapped or coiled around the lugs, thereby securely holding the chains assembled with the bands. The spurs, as shown in Fig. 2, are disposed at outwardly diverging angles so as to insure a most effective gripping or biting action in use, and also to space the points of the spurs as far apart as is consistent with the curvature of the band or the transverse diameter of the tire.

From the foregoing description, it will be seen that although the improvements of the present invention are simple in character, they will be thoroughly efficient for the purpose designed, and will coact in the presentation of a nonskidding attachment that will possess all the requisites necessary to make such a device of practical value.

Having thus described my invention, what I claim is:

1. In a device of the class described, the combination of a gripping member adapted to extend transversely of the tread of a wheel, spaced lugs on the opposite ends of said member adapted to project through the ends of adjacent connected links of a chain, and means connecting said lugs and extending over the connected ends of the chain links to retain said tread member in connection with the links.

2. In a device of the class described, the combination of a gripping member adapted to extend transversely of the tread of a wheel, attaching chains for retaining the gripping member on the tread of a wheel, and means on each end of said member extending longitudinally of the respective

chains and over the engaged ends of adjacent chain links to hold said member in connection with the chains.

3. In a device of the class described, the combination of a gripping member adapted to extend transversely of the tread of a wheel, spaced lugs projecting outwardly from each end of said member, link chains to retain said member upon the tread of a wheel, the lugs on each end of said member extending through adjacent links of one of

the chains, and a wire adapted to be connected at its ends to said lugs and extending over the engaged ends of the chain links to retain said gripping member in connection 15 with the chains.

In testimony whereof I hereunto affix my signature in the presence of two witnesses.

WALTER S. LAUFFER.
